UNITED STATES PATENT OFFICE.

JOSEPH W. RIDGWAY, OF LONG ISLAND CITY, NEW YORK.

COUNTERBALANCE FOR MOTOR-SHAFTS.

1,223,346.

Specification of Letters Patent. Patented Apr. 17, 1917.

Application filed July 17, 1916. Serial No. 109,864.

To all whom it may concern:

Be it known that I, JOSEPH W. RIDGWAY, a citizen of the United States, and a resident of Long Island City, county of Queens, 5 and State of New York, have invented certain new and useful Improvements in Counterbalances for Motor-Shafts, of which the following is a specification.

The invention relates to means for counter- 10 balancing motor-shafts having a plurality of cranks designed for simultaneous rotation at a high rate of speed, such as may be obtained, for instance, with the engines of self-propelled vehicles or similar machines.

15 It is now universally understood among mechanical engineers that there are unbalanced forces inherent or developed in plural-cylinder engines which must be counteracted in order to insure safe and 20 smooth running thereof when running beyond a certain velocity. The inertia and centrifugal force of each crank arm and crank pin are to be taken into consideration and compensated for, as they exert distor- 25 tive strains upon the engine shaft, if not counterbalanced by suitably distributed weights. The ponderal distribution, how- 30 ever, involves more than placing the cranks in static balance, as they should be in run- 35 ning balance as well. This being recog- nized, the custom has arisen to counteract 40 the unbalanced centrifugal forces by opposing thereto similar forces applied to the crankshaft as nearly as possible in the same

radial plane. But the remedy thereby af- 45 fforded is not satisfactorily effective, for the reason that, while the centrifugal forces to be balanced act radially to the axis of revolution, their resultant is a tendency to an-

40 gular motion relatively to the radial plane. In view of the foregoing, the present in- 45 vention has for its primary object to provide a novel, simple and efficient method and means of counteracting the lack of running balance in the plural-throw crankshaft of the type above mentioned, including such parts of the connecting-rods as may revolve with the crankshaft.

50 Another object of the invention is so to effect the balancing of forces that the strains on the shaft attachments will be limited to those generating rotative motion.

55 Other objects and advantages of the invention will in part be obvious and in part be described in the specification.

Reference will now be made to the accompanying drawings, in two sheets, for a detailed description of a few of the most approved forms of the invention, as applied to crank-shafts of motors having several cyl- 60 inders.

In the said drawings,—

Figure 1 is a side view of a three-bearing, 65 four-throw crankshaft counterbalanced in the manner provided for by the invention, part thereof being in sectional elevation;

Fig. 2 is a vertical transverse section on the line 2—2 of Fig. 1, looking toward the left, in the direction indicated by the 70 arrows;

Fig. 3 is a partly-sectioned side elevation of a similarly equipped crankshaft, illustrating a slightly different mode of construction;

Fig. 4 is a vertical section taken at right 75 angles to the latter view, again looking to the left, along the line 4—4;

Fig. 5 is a side elevation, partly in section, representing a two-bearing, four-throw 80 crankshaft to which is attached one of the simplest forms of the invention;

Fig. 6 is a transverse section taken vertically along the line 6—6 of the preceding view, exposing the left-hand portion thereof;

Fig. 7 illustrates another modified embodiment of the invention, applied to a two-bearing, four-throw crankshaft, the latter being shown in side elevation, with part of its equipment in section;

Fig. 8 is an upright section on the line 80 8—8 of Fig. 7, looking toward the left; and

Figs. 9, 10 and 11 are diagrams, respectively intended to depict the direction followed by the centrifugal forces, as generated in each instance, first, in the ordinary crankshaft; secondly, in a crankshaft provided with the customary counterweights; and, thirdly, in a crankshaft wherewith the present invention has been incorporated.

Referring now in detail to the drawings, 90 journals 21, 22 and 23, respectively, of the different forms of crankshafts represented in the drawings hereto annexed are alined in the usual manner and severally fitted in their bearings (not shown). Three such journals, it will be observed, are illustrated in Figs. 1 and 3, whereas only two appear in Figs. 5 and 7, as also in the diagrams 9, 10 and 11.

100 Crank arms 26, 27, of unequal lengths, are 110

formed on the various crankshafts, according to the common practice, and these arms are connected with one another by means of crank pins 28, of well-known formation. 5 As shown in Figs. 1 and 3, the crankshaft may have two long arms 26, and four short arms 27, all interconnected by pins 28. Or, as appears in Figs. 5 and 7, there may be only two long arms, two short arms, and a 10 correspondingly restricted number of crank pins. The invention is not limited to any particular quantity or grouping of the elements here enumerated. In the diagrams, Figs. 9, 10 and 11, a single long arm is indicated. This is sufficient to denote that, pursuant to recognized usage, the long arms 26, whether one or more, are located intermediately of the short arms 27 next adjoining the main bearings or journals 21 and 22 of the 20 several crankshafts. The joints or bearing portions of the crank pins, where the connecting-rods (not shown) grasp the same, are indicated by the reference numeral 29.

Referring more particularly to the said 25 diagrams, it will be observed, first, that an ordinary crankshaft having main bearings 21, 22, and oppositely extended crank arms 27, 26, 27, with interconnecting crank pins, as outlined in Fig. 9, is in static balance, 30 when at rest, assuming that the several parts have been correctly proportioned. But, when revolving at high velocity, the planes of revolution of the parts assembled at 29 will be as the arrows 30, and the centrifugal 35 forces developed will trend in like directions, because the weight of each group of parts 29 is not symmetrically disposed on opposite sides of its own plane, and the respective planes in which the two groups 40 revolve, being separated, naturally do not coincide. The resultant of the centrifugal forces acting in the two planes named is a tendency of the parts or masses 29 to travel in the opposed directions indicated by the 45 arrows 31, that is, both toward a median plane coinciding with that of the long arm 26 in the said Fig. 9. Consequently, the crankshaft is subjected to more or less distortion and vibration, with obvious injury 50 to the crank pins and connecting rods, according to the speed at which it revolves.

The method heretofore adopted to balance a crankshaft of the type represented in the preceding diagram is shown diagrammatically in Fig. 10. This method consists in effecting an even distribution of the masses on opposite sides of each plane of revolution, by attaching to the crankshaft a certain number of additional arms and 55 weights, as 34 and 35. The centrifugal forces to be balanced and the counter-acting forces generated by the balancing arms and weights are indicated by the arrows 30 and 37. This may properly be called an 60 convenient, expensive, and inadéquate method

of remedying the defect in the running balance of a crankshaft, as above enunciated.

No extra arms are added to the crankshaft, in carrying out the present invention, and only such counterweights are employed as have been ascertained to be strictly requisite to bring the respective planes of revolution of the masses to a common center. This is accomplished by attaching weights to the long arms of the crankshaft on the sides remote from their crankpins, so that the tendency of movement of the revolving weights will be toward a central plane, where it will nullify the similar tendency of the pins and connecting rods to move in the opposed direction. As diagrammed in Fig. 11, a weight 41, placed at each end of the long arm 26, on the opposite side from the crank pin 28, will develop upon being rapidly revolved centrifugal forces trending in the direction of the arrows 42, which result in forces trending in the direction of the arrow 43, which forces immediately encounter and balance those traveling in the direction of the arrow 31 and generated by the mass 29 adjacent to the said weight. This exemplifies the principle upon which the invention is based.

A convenient method of weighting a long arm on a crankshaft, in accordance with the 95 said principle, is to place a ring obliquely around the arm, as represented in Figs. 1 to 8 of the drawings. Such a ring may be attached to the arm and the form or structure thereof varied in numerous ways, as will 100 presently be explained.

As shown in Figs. 1 and 2, a ring 46, of uniform cross-section throughout its circumference, is made to surround approximately one-half the width of each long arm 26, on opposite sides of the arm's center, which in the present instance coincides with the center of the shaft's bearings or journals 21, 22 and 23. The ring is offset centrally, as at 47, so that it will cross the arm (either arm 26 to which it is applied) and throw its weight on the side thereof remote from the crank pin 28, at each end of the arm. To keep it in place, the ring is provided with lugs 48, arranged to bear against the 110 ends of the arm on the sides away from the crank pins, and bolted thereto, as at 49.

A similar construction is illustrated in Figs. 3 and 4, where the long arms 26 of the crankshaft appear as being equipped each 120 with a ring 46, offset at 47, and having inwardly-projecting lugs 48, adapted to receive bolts 49, all as above described. In the latter-named figures, however, the ring is further provided with a pair of inwardly-projecting flanges or stops 51, designed to bear on the ends of the corresponding long arm 26, directly opposite each crank pin 28. It will be noted that the stops 51 are respectively located at right angles to the lugs 130

48, within the ring 46, and the latter is held thereby as between angular abutments opposite to the crank pins.

A form of the invention analogous to that shown in the two preceding views is disclosed in Figs. 5 and 6, and therefore designated by the same reference numerals, with the exception of the ring 54, which has no central offset. But this ring is positioned 10 obliquely with relation to the long arm 26, as in all other instances.

In Figs. 7 and 8, the ring above referred to is replaced by an equivalent structure, composed of two segmental weights 56, 57, 15 united by tie-rods 58, 59, at the opposite ends thereof. As shown, the segmental weights are disposed transversely to the ends of the long arms 26 of the crankshaft, on the sides remote from the crank pins 28. 20 The weights are formed with angular recesses 60 therein in order that said weights may abut squarely against their respective ends of the long arms, and bolts 61, or similar fastenings, are employed to hold the 25 parts in their relative positions.

It will be readily perceived that the invention herein disclosed provides a novel system of balancing crank-shafts which possesses several advantages of a practical character. Thus, the system affords an easy, economical, and secure method of fastening balance weights. The counterweights used are inexpensive, and a couple only is needed to balance a crankshaft having four throws. 35 And, for example, as applied, the weights are more effective as fly wheels than the usual type of balance weights. In constructions based on the prior art, the balancing forces exert a radial stress on the crankshaft, 40 but in this improved construction they produce a stress which acts at an angle to the radial plane. In other words, the balancing forces, in the older constructions, act at right angles to the axis of revolution, whereas in 45 the present construction they act parallel to the axis of revolution.

The invention in its broader aspects is not limited to the precise construction shown and described nor to any particular construction by which the same may be carried 50 into effect, as many changes may be made in the details thereof without departing from the main principles of the invention or sacrificing its chief advantages. Thus, in the 55 foregoing description it has been assumed that all the parts of the crank shaft arrangement are in static balance or equilibrium so that the counterbalancing rings or segments have been shown and described as applied 60 symmetrically to the crank arms or concentrically to the axis of rotation of the crankshaft; but, it will be obvious that were the crank arrangement different, e. g., out of static balance, this condition might readily 65 be provided for by varying the form or dis-

position of the counterbalancing rings or weights to correspond, without affecting the principle and mode of operation previously set forth.

I claim:

1. The combination with a crankshaft arm having crank pins projecting respectively from the ends thereof in opposite directions, of weights connected with said arm on the sides remote from said crank pins. 70

2. The combination with a crankshaft arm formed with crank pins projecting laterally therefrom at or near its ends, of weights opposed to said crank pins connected with one another transversely of said arm. 75

3. The combination with a crankshaft arm having pins projecting oppositely from the sides thereof one at each end, of weights attached to both ends of said arm so as to revolve therewith in a plane bisecting a line 85 drawn through the mass centers of said pins.

4. The combination with a crankshaft arm having pins projecting from the ends thereof one at each side, of a ring disposed about said arm so as to throw its weight thereon 90 oppositely to said pins in substantially equal parts on the remote sides.

5. The combination with a crankshaft, an arm thereacross, and pins projecting laterally one from each end of said arm, of a ring 95 concentric with said crankshaft encircling the latter and the arm in an oblique direction.

6. The combination with a crankshaft, an arm transverse thereto, and oppositely projecting pins at the ends of said arm, of a 100 ring around the arm offset to divide the mass thereof remotely from said pins on opposite sides of the plane of revolution.

7. The combination with a crankshaft, an 105 arm extending transversely thereof, and pins projecting laterally from said arm at opposite ends, of a ring obliquely encompassing the arm, abutments on said ring arranged to bear against both ends of the arm on sides 110 thereof remote from said pins, and means for fastening said ends of the arm to said abutments each at a distance from the crankshaft.

8. The combination with a crankshaft arm 115 having pins projecting oppositely from the sides thereof one at each end, of weights attached to both ends of said arm so as to revolve therewith in a common plane oblique to their true planes of revolution. 120

9. The combination with a crankshaft arm, having crank pins projecting respectively from the ends thereof in opposite directions, of weights arranged on said arm in such manner that the balancing stresses affect 125 the crankshaft in lines parallel to its axis.

10. The combination with a crankshaft arm having pins projecting respectively from the ends thereof in opposite directions, of weights disposed relatively to said arm in 130

such manner that the balancing stresses affect the crankshaft partly in lines radially to its axis and partly in lines parallel to the same.

5 11. The combination with a crankshaft having a plurality of arms extending therefrom, of weights so arranged in relation to said arms that the balancing stresses affect the crankshaft partly on lines at an angle 10 to the axis thereof and partly on lines parallel to said axis.

12. The combination with a crankshaft weighted for static balance, a transversely disposed arm thereon, and pins projecting 15 laterally from said arm, one at each end, of a ring set around the arm so as to divide

the mass thereof remotely from its said pins on opposite sides of the plane of revolution.

13. The combination with a plural-throw crankshaft having arms provided with pitman connections, of balancing weights arranged to bear on said arms at the sides thereof remote from said connections.

14. The combination with a plural-throw crankshaft having arms provided with connecting-rod retainers, of balancing weights functioned to revolve with said arms at the sides thereof remote from said retainers.

In testimony whereof, I have signed my name to this specification.

JOSEPH W. RIDGWAY.
